UNITED STATES PATENT OFFICE.

EMIL ANDERSON, OF BANCROFT, IDAHO.

PUZZLE-BOX.

1,097,158.

Specification of Letters Patent.

Patented May 19, 1914.

Application filed November 7, 1912. Serial No. 730,048.

To all whom it may concern:

Be it known that I, EMIL ANDERSON, a citizen of the United States, residing at Bancroft, in the county of Bannock and State of Idaho, have invented new and useful Improvements in Puzzle-Boxes, of which the following is a specification.

My invention relates especially to the class of boxes, and aims to provide a lid for a box which cannot be opened except by the manipulation of certain elements carried thereby such as will be clearly set forth in the hereinafter appearing description.

The box may be used to hold any substance or material, but it will be especially noted that it is readily applicable for use as a cash box.

Broadly my invention consists of a box comprising a body portion having a cover 20 in pivotal-slidable engagement therewith, this cover being held in its normal position through the medium of an arrangement of wedge shaped members, each member being inserted in a certain way that if the cover 25 is desired to be removed, the wedges have to be withdrawn in rotation, that is, the first wedge always first so as to allow the others to be taken out. After all the wedges are removed, the cover can then be slid backward 30 upon its pivot to allow access to the contents of the box.

The greatest of stress is laid upon the simplicity of my invention and it is thought that the advantages and novel features of 35 the same will be readily comprehended from the hereinafter appearing disclosure.

With the above and other objects in view, my invention relates to such details of construction and in the arrangement and combination of the several parts as will be hereinafter fully described and specifically pointed out in the appended claim.

In describing my invention in detail, reference will be had to the accompanying 45 drawings wherein like characters denote like or corresponding parts throughout the several views, and in which:—

Figure 1 is a plan view of my invention showing different, of the wedged pieces partly 50 withdrawn as shown in dotted lines. Fig. 2 is an end view of the device. Fig. 3 is a plan view of the box showing a portion of the cover, which is in pivotal relation therewith 55 swung backwardly. Fig. 4 is a side elevation of my invention as the parts are in Fig. 3. Fig. 5 is a longitudinal sectional view of my

invention showing the cover in an open position. Fig. 6 is a plan view of the device showing the cover in an open position. Fig. 7 is a sectional view taken on line 7—7 of Fig. 1. Fig. 8 is a perspective view of a detail, and Fig. 9 is a sectional view taken on line 9—9 of Fig. 1.

In the accompanying drawings wherein is illustrated the preferred form of my invention, the numeral 10 designates the box proper or what will be hereinafter termed as the body portion of my invention. This box may be of any desired type and formed from any material, I, not limiting myself to either the construction or to the material used and it is to be understood that the form shown in the drawings is merely used to illustrate the efficacy of the device.

Partitions 11 are provided in the box, 75 which, if the box is to be used as a cash box, divide the same into compartments for holding bills of different denominations or change if it is so desired.

One end of this box has a substantially 80 wedge shaped undercut slot 13 formed therein, for the reception of a correspondingly shaped member 14, the latter being considerably longer than the slot so that a portion 85 thereof projects beyond the upper face of the box as illustrated. The other end of the box is also provided with a substantially wedge shaped member 15 which has a substantially dove-tail projection 16 formed thereon which projects above the upper face of the box and 90 serves the purpose that will be hereinafter fully set forth. This wedge is fast in the body portion and if it is desired can be formed out of the same and is just used for the subsidiary function of providing a 95 "blind" so that persons trying to gain access to the box under false pretenses will become confused in the manner in which the wedges operate.

A cover, such as designated by the numeral 100 17 is provided which has a slot 18 provided therein for the reception of a pin 19, the latter being carried upon the body portion as is clearly shown. By this arrangement, it will be recognized that the cover is held in 105 pivotal-slidable engagement with the box and removed to any desired position.

The rear end of the cover is provided with a dove-tail opening 20 which receives, when the cover is in its normal position, the 110 upper portion of the wedge 14, while the opening 21 which is formed in the other end

of the cover receives the projection 16 on the wedge 15. It will now be recognized that when the cover is in its usual position, its lateral movement is prevented. However, if the wedge 14 is removed, it can then be slid backwardly upon its pivot and swung to the side to allow access to be had to the contents of the box.

The cover above mentioned consists of a body portion 17 having a raised portion 22 provided thereon, the latter element having its face cut slanting and beveled as shown at 23, this being for the purpose that will be hereinlater fully set forth. The edge of the raised portion extends diagonally across the body portion of the cover as is obvious and it will be noted that the slanting face 24 of the subordinate cover 25 is correspondingly formed so that a secure and snug joint between the subordinate cover and the raised portion will be had. The subordinate cover as mentioned is also pivoted upon the pin 19, however, it has no slidable movement at any position.

For the purpose of receiving a wedge block 26, the raised portion 22 and subordinate cover 25 are provided with correspondingly shaped cut out portions 27 and 28 respectively, which, when the covers are in place, are in alinement with each other and form a suitable recess as is shown. Dovetail cut out portions 29 and 30 are also provided in the raised portion 22 and cover 25 respectively, which, when in alinement with each other, receive a block 31, the cut out portion 32 in the latter being in alinement with the recesses 27 and 28 so that it may also receive a portion of the wedge 26.

It will now be recognized that as soon as the wedge 26 is secured in place, the cover 17 and the subordinate cover 25 will be securely held in place and to remove the cover 17 from its position, the wedge 14 together with the wedge 26 have to be pushed out of their respective receiving slots.

Fixed upon the block 31 and by any suitable means is an operating member 33 for the block which serves the purpose of covering the joint made between the block and its respective receiving slots. By the provision of this member, it will be recognized that all danger of the exposure of the pivoted cover into different elements is obviated. Another wedged member 34 is provided and received into a correspondingly formed groove, as shown at 34', this wedge serving as a "blind" to cover an opening in the bottom of the groove, the opening being provided so that the wedge 14 can be drawn out after the subordinate cover has been turned upon its pivot. This wedge is provided upon the subordinate cover, however, another wedge 35 is provided upon the raised portion 22,

the wedge 35 being fast upon the offset portion and cannot be removed at all, this member serving as a blind.

In the operation of my invention, the covers and wedges are disposed in the position clearly shown in full lines in Fig. 1, and if the box is desired to be opened, the operator first removes the wedge 26, then moving the block 31 and member 33 within the slots 29 and 30 until the block 31 is in a position to allow the subordinate cover to be revolved upon the pin 19. The wedge 34 is then removed and the wedge 14 is then drawn out through the opening in the bottom of the slot 34' in which the wedge 34 is mounted which will allow the cover proper to be moved backwardly upon the pin and consequently upon its fulcrum to expose the interior of the box.

The greatest of stress is laid upon the simplicity of my invention and it is thought that the advantages and novel features of the same will be readily comprehended from the foregoing disclosure.

I desire it to be understood that I may make slight changes in the construction and in the arrangement and combination of several parts, provided, however, such changes fall within the scope of the subjoined claim.

Having thus fully described my invention, what I claim as new and desire to secure by Letters Patent is:—

A box provided with a tapered groove in one end, a major cover member slidably and pivotally mounted upon the top of said box and provided with a notch registering with the tapered groove of said box when said cover is in a closed position, an auxiliary cover section pivotally mounted above said major cover section and provided with a notch registering with the groove of said box when said auxiliary cover section is in a closed position, a wedge passing through the notch of said auxiliary section into the groove of said box to lock said major cover section against longitudinal movement when in a closed position, the major cover section being provided with a shoulder having its upper face flush with the upper face of said auxiliary cover section and said cover sections provided with tapered grooves registering when said auxiliary cover section is in a closed position, a wedge passing through the alined grooves of said cover sections, and means carried by said major cover section and engaging said wedge to prevent withdrawal of the same when in a normal position.

EMIL ANDERSON.
